UNITED STATES PATENT OFFICE.

FRANK G. WHEELER, OF APPLETON, WISCONSIN, ASSIGNOR TO BLEACH PROCESS COMPANY, OF APPLETON, WISCONSIN, A CORPORATION OF WISCONSIN.

ELECTRODE.

1,279,192.

Specification of Letters Patent. Patented Sept. 17, 1918.

Application filed July 21, 1916. Serial No. 110,520.

To all whom it may concern:

Be it known that I, FRANK G. WHEELER, a citizen of the United States, residing at Appleton, in the county of Outagamie and State of Wisconsin, have invented certain new and useful Improvements in Electrodes, of which the following is a specification.

This invention is an electrode which is designed especially for use as an anode in the electrolysis of chlorid solutions, although obviously susceptible of use in many other relations. In its preferred embodiment the electrode comprises a bar, rod, or the like of graphite or other form of carbon which constitutes the active anode, and a metallic terminal in internal screw-threaded engagement with the carbon, that portion of the carbon which surrounds the metallic terminal being so impregnated with a liquid-proofing composition as effectively to prevent access of the electrolyte or its decomposition products to the metal of the terminal. The portion of the metal terminal which engages the interior of the carbon bar is preferably formed of a fusible metal or alloy, such as hard lead, whereby the metal elements of the terminal may be recovered from the carbon stubs at the end of their period of useful life. In use the electrode is so mounted in conjunction with the cover or other portion of the cell wall that the active carbon electrode lies wholly within the cell, the metallic terminal extending through the cell-cover or other portion of the cell wall, for connection to the current leads. The word "carbon" as employed herein includes graphite.

An illustrative embodiment of the invention is shown in the accompanying drawings, wherein the figures are central vertical sections of electrodes embodying the invention, the said figures illustrating also certain preferred modes of mounting the electrodes in the electrolytic cell.

Referring to Figure 1, 1 indicates the upper portion of a graphite bar constituting the anode proper, and 2 an internally screw-threaded recess therein. The conductor 3, which may be of tinned steel, copper, bronze or other metal or alloy extends axially into the recess 2, and is mechanically and electrically connected with the graphite by a body 4 of fusible metal, usually hard lead. This metal is cast upon the conductor

3 before the latter is inserted in place in the carbon, and is provided as shown with screw-threads for engaging the internal threads of the carbon bar. Preferably the recess 2 is of slightly greater depth than the screw-threaded portion of the lead connector 4, and the latter is provided at its upper or outer portion with a shoulder or flange 5, the purpose of this arrangement being to permit the shoulder 5 to contact firmly with the upper face of the carbon bar in such manner as to increase the area of effective electrical contact therewith. The fusible metal may enter one or more recesses 6 in the conductor 3 for the purpose of preventing displacement under torsional strains when the metallic portion of the terminal is screwed into the carbon; or this result may be obtained by providing any other form of positive engagement between the metal members 3 and 4.

In a construction of this type it is absolutely necessary for the maintenance of a permanently effective electrical connection between the lead and the carbon that any access to the metal of the electrolyte, or of chlorin or other products of decomposition thereof, should be prevented. This result I accomplish by impregnating the adjacent portions of the carbon with a suitable filling material. To this end I introduce the impregnating liquid or composition into the recess in the upper portion of the carbon bar, and thereafter screw the metal terminal firmly to its seat. Under these conditions the plunger action of the terminal upon the liquid composition in the recess forces the latter into the pores of the carbon, thus providing the most effective conditions for pressure impregnation. While my invention is not limited to any particular impregnating composition, I may use corn-cottonseed-fish-tung- linseed-oils or like glycerids; or such asphaltic products as gilsonite, elaterite, etc.; or preferably mixtures of a glycerid and an asphaltic product, thinned if necessary by a light hydrocarbon such as gasolene.

The employment of lead in the manner above described not only provides a highly effective and permanent electrical connection with the carbon throughout the life of the latter, but permits the metal elements of the terminal to be readily recovered in

usable condition. For this purpose it is merely necessary to heat the stub of the electrode in order to melt the fusible metal or alloy, when the conductor can be withdrawn and the molten metal poured out in condition for re-casting.

Although I prefer in every case to use a fusible metal between the conductor bar and the carbon which constitutes the active anode, my invention is not limited thereto, inasmuch as excellent results are obtainable with proper impregnation when using a terminal consisting of an integral metal part, and comprising for example a screw-threaded portion, shoulder, and shank of brass or bronze, as indicated at 7 in Fig. 2.

An electrode constructed as described above must be so mounted in connection with the cell-cover or other portion of the cell body as effectively to protect all metal parts against the action of chlorin or other corrosive products; at the same time it is desirable that the carbon portion of the electrode should lie wholly within the cell, since in this way it can be most fully utilized. These results may be accomplished as illustrated in Fig. 1 by passing the conductor 3 through an aperture 8 in the stoneware or other cover 9 of the cell, a gasket 10 of soft rubber or the like being provided between the upper surface of the carbon and the lower face of the cover, the whole being drawn into firm engagement by means of a nut 11 on the conductor 3. 12 indicates a lead washer, and 13 the anode conductor or bus bar. The lower surface of the cover may be recessed as indicated at 14 to receive the shoulder 5 of the metal terminal.

The cell-cover may if desired be of iron as indicated at 9' in Fig. 2, being provided of course with an internal resistant lining indicated at 9''. In such cases the present form of connector presents the advantage that the conductor bar may lie flat upon the top of the cell, whereby the whole cover serves as a current conductor and distributor to the anodes at one and the same time.

When the carbon portion of the anode is to be mounted some distance below the cell-cover I provide a sleeve of hard rubber, stoneware or other inert material, as indicated at 15 in Fig. 2, this sleeve encircling the shank of the terminal and bearing upon soft rubber gaskets 10' located between the sleeve and the cell-cover and carbon anode respectively. This sleeve may of course be of any desired thickness and may be recessed as at 14' to receive the shoulder of the terminal.

I claim:—

1. An electrode comprising a carbon portion provided with a recess, a metallic conductor extending into said recess, and a body of fusible metal between said conductor and the carbon and engaging the latter by means of a screw-thread, the portion of the carbon adjacent the metal being impervious to the electrolyte or its decomposition products. 60 65

2. An electrode comprising a carbon body provided with a recess having an internal screw thread, the portion immediately surrounding the recess being impregnated with an acid proof substance, a body of fusible metal having an external screw thread to fit the threads of said recess and a metallic terminal securely locked in the body of fusible metal. 70 75

3. In combination with an electrolytic cell having a cover, an electrode comprising a carbon portion provided with a recess having an internal screw-thread, a metallic terminal extending into said recess and engaging the threaded portion thereof, the portion of the carbon adjacent the metal being impervious to the electrolyte or its decomposition products, a gasket encircling the terminal and lying between the carbon body of the electrode and the interior face of the cell cover, and means for forcing the carbon body of the electrode into contact with said gasket to make a liquid-tight joint therewith. 80 85 90

4. In combination with an electrolytic cell having a cover, an electrode comprising a carbon portion provided with a recess having an internal screw-thread, a metallic terminal extending into said recess and engaging the threaded portion thereof, the portion of the carbon adjacent the metal being impervious to the electrolyte or its decomposition products, an insulating sleeve encircling the metallic terminal between the carbon body of the electrode and the interior face of the cell cover, and means for forcing said elements into contact to make a liquid-tight joint. 95 100 105

5. An electrode comprising a carbon body and a metal terminal, the portion of the carbon adjacent the metal terminal being impregnated with a mixture containing asphaltum and a glycerid. 110

In testimony whereof I affix my signature in presence of two witnesses,

FRANK G. WHEELER.
